UNITED STATES PATENT OFFICE.

JOHN H. HEARDING, OF DULUTH, MINNESOTA.

ORE-MIXING POCKET.

Application filed November 17, 1920. Serial No. 424,753.

To all whom it may concern:

Be it known that I, JOHN H. HEARDING, a citizen of the United States, residing at Duluth, in the county of St. Louis and State 5 of Minnesota, have invented certain new and useful Improvements in Ore-Mixing Pockets, of which the following is a specification.

This invention relates to a new and improved method and means for securing uniform mixtures of loose materials or more specifically for securing a uniform grade or quality of ore by means of a mixing process whereby several car loads of ore are 15 thoroughly intermingled to provide, for use in the furnaces, a mixture having a constant analysis although the several cars contain ores of differing analyses.

The invention is of particular application 20 in connection with the handling of iron ores and will be described in connection with such use. It is obviously, however, of broad application where similar results are desired in the handling of other materials.

25 In the operation of blast furnaces for the production of pig iron it is highly desirable that the ore fed to the furnace be of a uniform grade, that is, that the chemical analysis of the ore be constant. This is desirable not only in order to secure a uniform 30 product, but to facilitate a uniform working of the blast furnaces.

In practice it is customary to take samples 35 from a certain number of the cars in which the ore is shipped, the combined analyses representing the content of the ore as a whole. As the cars are received, the ore is dumped from the cars into pockets or bins and withdrawn from the bins in other cars 40 for use in the furnaces. In these various operations of handling the ore in transit from mine to furnace, a certain amount of mixing occurs. This mixing is, however, not sufficient to cause as thorough an intermix- 45 ture as is desirable and the ore to the furnace does not run as uniformly in content as is preferred.

In the normal dumping of ores from cars 50 into storage bins there is a certain amount of intermixture, but there is, nevertheless, a more or less pronounced stratification in the bin caused by the successive dumpings of the various cars. There is some mixing action as the ore is drawn from the bin but not 55 sufficient in amount to accomplish the desired uniformity.

If the first bin or pocket is caused to discharge into a second bin, there is still a certain amount of stratification in the second bin, although it is less pronounced than in 60 the original bin. An additional mixing is caused as the ore is drawn from the second bin into the cars and the mixture delivered to the furnaces is much more uniform in content than is the case where a single bin 65 is used.

A still further improvement in the mixing is, however, very desirable. Obviously any means tending to reduce stratification in either or both bins will have the result of 70 producing a more uniform ore as delivered finally to the furnaces.

It is an object of the present invention to provide a new means whereby ores or materials of like character may be intermingled 75 and mixed to secure a uniform content. It is a further object to accomplish the desired result without the necessity of any additional handling of the material other than that normally required. It is also an object 80 to provide means of the character described which are simple in construction, positive in operation, and relatively inexpensive of installation. Other and further objects will appear as the description proceeds. 85

I have illustrated a preferred embodiment of my invention in the accompanying drawings, in which—

Figure 1 is a side elevation, partly broken away, showing a storage bin structure 90 equipped with my invention; and,

Figure 2 is a cross elevation of the structure of Fig. 1.

The ore or similar material is received 95 from cars 3, run in upon either of the ele- vated tracks 4 or 5. The receiving bin 6 is located below these tracks. Below the tracks and adjacent the top of the bin are located the deflecting vanes or wings 7 meet- 100 ing in a line at the top and diverging there- from in such manner as to throw the mate- rial against the sides of the bin. The chute 8 is provided at the lowest point of the receiving bin and it leads into a second or delivery bin 9. The bin 9 is also provided 105 with deflector wings 10 adjacent the chute 8. The delivery chute 11 leads from the lower end of the bin 9 and is adapted to deliver material to cars 12 upon lower track 13.

In the use of this bin construction, mate- 110 rial is preferably alternately dumped from tracks 4 and 5 into the bin 6, the alternate

dumping from the different tracks supplying material at differing points and aiding in its distribution and intermixture. The deflector wings 7 tend to throw the material against the lateral walls of the bin and are material aids in thus distributing the contents of a car thoroughly over the bin area. The several cars will, however, provide differing layers of material more or less uniformly distributed over the lower part of the bin, the dumping from different tracks and the use of the deflecting vanes serving to aid in distributing the material.

When the upper bin 6 has been filled to the desired point or has received the contents of the cars containing a desired lot of material, the gates to the chute 8 may be opened and a stream of ore will pass out of the chute 8 against the deflector 10 and will be thrown against the side walls of the bin 9.

In the flow through the chute 8 and over the deflectors 10 and the distribution in the bin 9 the strata of the bin 6 are thoroughly disrupted and the ore in the second or delivery bin will be substantially a uniform mixture. The material undergoes a certain amount of mixing due to the movement in bin 6 incident to its flow through the chute 8 and a similar movement and mixing occurs as the material is drawn off from the bin 9 by the chute 14 into cars 12 for transportation to the blast furnaces. Any individual car 12 will receive a substantially uniformly mixed lot of material, the resultant of the various grades of material dumped into the upper bin, and successive cars 12 will receive the same material until the contents of the bin are exhausted.

An important feature of my invention lies in the fact that it involves no rehandling of the material other than that incident to

its normal movement. The bins 6 and 9 take the place of the usual storage bins where the ore is stored upon arrival from the mine until needed for the furnaces. The flow over vanes 7 and 8 and through chute 8 is all accomplished by gravity and the only additional labor required is the opening and closing of chutes 8 at the proper time. The structure itself is simple and its use involves no excess labor or power cost, while it results in a much more uniform mixing of the ore with consequent advantages in smelting.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention.

I claim:

An ore storage and mixing structure adapted to intermix ore stored therein during the passage of said ore through the structure under the influence of gravity, said structure comprising an upper receiving bin, a plurality of receiving tracks passing above spaced portions of said bin, deflector vanes placed in the upper portions of said bin below the tracks, a lower discharge bin, a restricted chute connecting the upper and lower bins, deflector vanes located in the lower bin below said chute, and a restricted discharge chute at the lower portion of the lower chute, the deflectors and restricted chutes serving to alternately distribute and intermix the ore.

Signed at Duluth, Minnesota, this 12 day of November, 1920.

JOHN H. HEARDING.
